UNITED STATES PATENT OFFICE.

HAYDEN HOMER TRACY, OF BERKELEY, AND HARRY EUGENE BOYRIE, OF SAN FRANCISCO, CALIFORNIA.

SETTING FOR BOILER-FURNACES.

1,003,548.

Specification of Letters Patent. Patented Sept. 19, 1911.

Application filed April 29, 1911. Serial No. 624,251.

To all whom it may concern:

Be it known that we, HAYDEN HOMER TRACY, a citizen of the United States, and resident of the city of Berkeley, in the county of Alameda and State of California, and HARRY EUGENE BOYRIE, a citizen of the United States, and resident of the city of San Francisco, in the county of San Francisco and State of California, have jointly 10 invented a certain new and useful Improvement in Settings for Boiler-Furnaces, of which the following is a specification.

This invention relates more particularly to settings for boilers and installations for 15 steam-making,—but is also applicable with equal advantage to heating or other types of furnaces where the settings involve construction such as the ordinary brick-work, from which a portion of the heat generated 20 within is absorbed by and radiated from the exterior walls.

The general object of the improvement is to save and utilize such radiated heat, which is ordinarily wasted, by employing same in 25 the pre-heating of the air introduced to the furnace chamber, for promoting or aiding the combustion of the fuel, and consequently economizing in the use of such fuel by reducing the amount of heat required in 30 the process of combustion for raising the temperature of the air from the external atmospheric degree up to the temperature of the furnace, and obtaining the maximum internal radiation from any given quantity of 35 fuel,—thus insuring the greatest possible application of heat arising from its combustion to the instrumentalities (such as tubes, drums, boilers,—and the like) designed to be acted upon by such direct and radiated 40 heat.

To these useful ends, the invention consists, briefly speaking, in what may be termed a waste-heat-recovering instrumentality applied externally of the main furnace or boiler setting, in communication at 45 definite points both with the external air and with the fire chamber,—whereby the air is first acted upon by the heat ordinarily dissipated or lost by external radiation 50 from the furnace walls, and then fed in a consequent heated condition to the fire for promoting combustion of the fuel.

For full comprehension of our invention, and of convenient and preferred means for 55 carrying same into practical and economical

operation, reference must be had to the accompanying drawings forming part of this specification.

In said drawings, similar numerals of reference indicate like parts in the several 60 figures.

Figure 1 is a longitudinal sectional elevation of a water-tube boiler and furnace, embodying the essential features of our invention. Fig. 2 is a sectional plan view of 65 portions thereof, taken on the line 2, 2, 2, Fig. 1. Fig. 3 is a front sectional elevation.

These drawings show the improvement in connection with a water-tube boiler, and furnace of a well-known type, the following 70 specified ordinary instrumentalities thereof being only incorporated for purposes of illustration, it being manifest that we are not limited in the application of our invention 75 thereto, as the essentials allied to our devices are simply a furnace-setting and instrumentalities therein arranged for effecting combustion of fuel and radiation and conduction of heat therefrom. Here, the numerals 20 and 21 indicate the front and 80 rear brick walls, respectively, of the boiler setting, 22 the aperture in the latter leading to the smokestack, 23 the bridge wall, 24 the grate, 25 the arch in the fire chamber, 26 the top covering, and 27 the side walls, all of the 85 usual or any approved construction and arrangement.

28, 29 and 30 are the usual steam and water drums carried transversely in the setting, at a high level, with the usual circulation pipes, and 31 the mud-drum set at a 90 low level.

32, 33 and 34 are banks of water-tubes leading down from the above steam and water drums and opening into the mud 95 drum; 35 and 36 are inclined baffles of fire-tile built in between the several banks of water-tubes, and performing their usual function of directing the products of combustion in their proper course toward the 100 smoke-stack.

In the adaptation of our invention to a boiler-furnace of the above or any similar class, we introduce at or near the draft entrance 37 of each ash-pit an easily-control- 105 lable damper 38, preferably formed of a plurality of foldable slats pivoted within the walls of a suitable frame fitting the opening in the brick front wall, the normally-closed door 40 affording access thereto being 110

arranged forward of this damper in the front plate, as will be hereinafter set forth.

Extending wholly across the front wall 20, and slightly beyond the side-walls 27 of the furnace-setting, we arrange a substantial air-chamber 41, the same being formed between the steel plate front 42 and the face of the brick wall 20,—suitable closed-off casings 43 for the fire-door, and 44 and 45 for the necessary front tube-openings, respectively, being extended from the front plate 42 across this transverse air-chamber 41 and through the registering openings in the brick front wall 20, in such manner as to allow of the free circulation of air circumferentially of such casings. This transverse air-chamber 41 is open at the top to the external air, as seen at the points marked by the arrows a , a' , in Figs. 1 and 3,—and is also extended into supplementary air-chambers 46, one extending horizontally, parallel with and exteriorly of each of the side-walls 27 of the main setting, so as to open into and communicate with the front chamber 41 at the front corners, as indicated by the arrows a^1 , a^2 , in Figs. 2 and 3. These supplementary air-chambers 46, for convenience of setting, need not extend upward from the floor as far as does the front chamber 41, but may stop short and be closed at the top a short distance below the lower lines of the steam and water drums 28, 29, 30, as shown in the broken-away portion of Fig. 1, and at the sides of Fig. 3. These chambers 46 extend backward along the greater portion of the more intense heat-radiating portions of the furnace side-walls, as in Figs. 1 and 2, and are open from top to bottom at their rear ends to permit of the free entrance of external air at the points marked by the arrows a^3 , a^4 .

The front wall 42 of the air chamber 41 is formed as stated, of the ordinary sheet-steel front plates, employed as a finish or facing in boilers and settings of the class here dealt with,—and the outer walls 46 of the side or supplementary air-chambers 46 are preferably of the same material,—as

we have found that the induced and moving currents of air passing through such chambers from their inlets to and through the draft openings 37, and thence through the furnace, and mingling with the products of combustion, drawn away to the smoke-stack, are sufficient to prevent any appreciable radiation of heat through such walls. We may, however, reinforce these walls with a non-conducting lining, if found desirable.

The operation of our invention will be clearly understood from the foregoing and from the drawings, but we may further explain that external air passes by natural suction or draft into the chambers 41 and 46, at the points marked by the arrows a , and a' , respectively, and after circulating as shown by the arrows a^1 , and taking up radiated heat from the adjacent brick walls of the setting, is drawn through the damper-controlled draft openings 37 into the ash pit, whence it passes up through the grate promoting combustion thereat and throughout the furnace as already fully set forth.

What we claim and desire to secure by Letters Patent is as follows:

In a furnace,—the combination with the main front wall of the setting having a damper-controlled air-draft-inlet to a point underneath the grate,—of an air-chamber arranged exteriorly thereof and having a cold air opening at its upper portion,—and supplementary air-chambers at the sides of the setting in communication with said front air chamber and open at their rear for receiving cold air from the exterior,—the whole being adapted to recover waste heat radiated from the furnace walls and apply same to pre-heat the air used to promote combustion in the furnace.

In testimony whereof, we have signed in the presence of the two subscribing witnesses.

HAYDEN HOMER TRACY.
HARRY EUGENE BOYRIE.
